UNITED STATES PATENT OFFICE.

BYRON L. BACOT, OF McCOMB, MISSISSIPPI.

TILE-MOLDING MACHINE.

1,419,198.

Specification of Letters Patent. Patented June 13, 1922.

Application filed June 23, 1921. Serial No. 479,889.

To all whom it may concern:

Be it known that I, BYRON L. BACOT, a citizen of the United States, residing at McComb, in the county of Pike and State of Mississippi, have invented new and useful Improvements in Tile-Molding Machines, of which the following is a specification.

This invention relates to machines for molding roofing tiles, and its object is to provide a very simple and efficient machine of this kind, and also one which is rapid in operation.

The invention also has for its object to provide a machine for forming the tile with depending bottom lugs.

The objects stated are attained by means of a novel combination and arrangement of parts to be hereinafter described and claimed, and in order that the same may be better understood, reference is had to the accompanying drawings forming a part of this specification.

In the drawings,

Figure 1 is a side elevation of the machine;

Fig. 2 is a plan view thereof;

Fig. 3 is a cross-section on the line 3—3 of Fig. 2;

Fig. 4 is an enlarged cross-section on the line 4—4 of Fig. 2 showing the mold filled;

Fig. 5 is a plan view minus a pallet, and

Fig. 6 is a cross-section on the line 6—6 of Fig. 5.

Referring specifically to the drawings, 10 denotes a pallet on which is placed the cement or analogous material employed in the construction of the tile, said pallet being shaped to give the tile the desired shape on one side. The other side of the tile is shaped 40 by a forming tool 11 which is placed transversely of the mass of cement on the pallet and run across the mass to compress and shape the same. The cement or other material is shown at 12. The machine is designed

45 more particularly for molding a roofing tile which is rectangular in outline and corrugated or fluted to form ridges and depressions running from the top to the bottom. The tile, on its under side, a short distance 50 from the edge which is at the bottom when the tile is laid, is also to have two laterally spaced securing lugs as shown at 12^a in Fig. 4, which lugs are somewhat hook-shaped, the hooks being outwardly or laterally presented, for engagement by the nails whereby the tile is secured in place on the roof.

The supporting frame of the pallet 10 is a rectangular box-like member having front and rear end walls 13 and 14, and side walls 15. The front end wall 13 is not as high as the other walls and it is provided with a hinged extension 16 rising to the height of the latter and forming an end gate which seats between the side walls 15. The hinge of the end gate 16 is shown at 17, and at 18 is shown a lever for operating said gate, said lever being pivoted to the wall 13 as shown at 18^a.

The frame hereinbefore described is supported by legs 19 suitably braced by intermediate and bottom cross bars 20 and 21 at the sides, and inside the frame are front and rear supporting strips 22 and 23 for the pallet 10. The frame also carries corner blocks 24 through which are threaded vertical screw stems 25 which support the strips 22 and 23 at their upper ends. It will therefore be seen that the pallet-supporting strips are vertically adjustable so that the pallet may be properly positioned relative to the top edges of the walls 14 and 15 and the end gate 16, according to the desired thickness of the tile to be made.

The following means are provided for molding the hook-shaped lugs 12^a of the tile:

Near the front end of the pallet 10, the latter has two laterally spaced apertures 26, and on the bottom of the pallet, at the side of each aperture is a lug 27. In the front face of the lug 27 is a cavity 28 which is in direct alinement with the aperture 26, and hence the material on the pallet can pass through said aperture into the cavity to fill the same, the cavity conforming in shape to the shape of the lug 12^a to be formed on the tile.

The cavities 28 of the lugs 27 are open in front and also on one side, and hence some retaining means for the material must be provided, which means will now be described.

Carried by supports 29 on the walls 15, is a transverse shaft 30 which is stationary and pivotally supports two plates 31 and 32 which face each other. The plate 31 has hinge arms 31^a and the plate 32 has hinge arms 32^a, the same being journaled on the shaft 30. On that side of the plate 32 which is opposite and facing the plate 31 are two pairs of lugs, adapted to co-operate with the lugs 27, the members of said pairs of lugs

being indicated by the reference numerals 33 and 34. The lugs 33 are positioned to come alongside the inner sides of the lugs 27, and the lugs 34 to come along the outer sides of said lugs 27 through which the cavities 28 open, so as to close up the latter, as clearly shown in Fig. 4. The plate 31 is designed to be swung against the front face of the lugs 27 to close up the cavities 28 in front.

The cavities 28 are closed up at the side and in front in the manner described by swinging the plates 31 and 32 toward each other, this operation being simultaneously effected by a lever 35 having actuated connections with the plates. The lever 35 is on a rock-shaft 36 supported by the cross-bars 21 and provided with a rocker arm 37. Two angle or bell-crank levers 38 and 39 are pivotally connected as shown at 40. One arm of the angle lever 38 is connected to an arm 41 extending from the plate 31, and the other arm of said lever is connected by a link 42 to the rocker arm 37. One arm of the angle lever 39 is connected to an arm 43 extending from the plate 32, and the other arm of said lever is connected by a link 44 to the rocker arm 37. The operating lever 35 works in a guide 45 carrying a suitable spring latch device 46 for locking said lever when it has been swung to place the plates 31 and 32 in operative position.

In operation, the pallet 10 being in place, and the plates 31 and 32 having been swung toward each other to close up the cavities 28, as hereinbefore described, the cement or analogous material is placed on the pallet to a height slightly above the plane of the top edges of the side walls 15. The forming tool 11 is now placed transversely of the material and run over the same from the rear to the front, it being seated on the top edges of the side walls 15 to be guided thereby. The forming tool compacts the cement or other material and also shapes the top surface and the longitudinal or side edges of the tile, the bottom surface being shaped by the pallet itself, and the lugs 12^a being molded by the cavities 28. The finished tile, with the pallet, is readily removed from the machine upon swinging the end gate down, after operating the lever 35 to spread the plates 31 and 32 and thereby take the plate 31 and the lugs 33 and 34 clear of the lugs 27 on the bottom of the pallet. The tops of the rear end wall 14 and of the front end gate 16 are ridged to conform to the ridged contour of the bottom of the forming tool, and the top edges of the side walls 15 have guide grooves 47 for guide lugs 48 on the bottom of the forming tool 11. The end wall 14 and the end gate 16 rise slightly above the pallet to form the ends of the tile and the guide grooves 47 are continued therethrough, as shown in Figs. 2 and 5, in order

that the forming tool may be slid over said wall and end gate and be carried along the entire length of the pallet. The front end of the pallet has a small top recess 49 to mold a transverse rib on the bottom of the tile at 70 this end. The pallet and the forming tool are also shaped to produce in the finished tile a longitudinal rib 12^b adjacent to one edge, and a similar groove 12^c adjacent to the other edge. When the tiles are assembled on the roof of the rib of one tile seats in the groove of the adjacent tile in the row.

I claim:

1. In a tile molding machine, a frame, corner blocks in the frame, screws threaded vertically through the corner blocks, cross strips carried by the screws at the respective ends of the frame, and a pallet seating on said cross strips. 80
2. In a tile molding machine, a frame consisting of side and end walls, and a gate on one of the end walls, pallet-supporting means in the frame, and a pallet removably seating on said means. 85
3. In a tile molding machine, a frame, a pallet supported in said frame and having apertures, lugs on the bottom of the pallet, said lugs having cavities in one of their faces, and said cavities being in alinement with the apertures of the pallet and opening 95 through one side of the lugs, and means for closing the open front and side of the cavities. 90
4. In a tile molding machine, a frame, a pallet supported in said frame and having apertures, lugs on the bottom of the pallet, said lugs having cavities in one of their faces, and said cavities being in alinement with the apertures of the pallet and opening 100 through one side of the lugs, oppositely swinging plates between which lugs are 105 adapted to seat, one of said plates being adjustable to seat over the faces of the lugs having the cavities, and the other plate having lugs and being adjustable to position its lugs at the sides of the lugs of the pallet through which the cavities open to close up the same, and means for operating said plates. 110
5. In a tile molding machine, a frame, a pallet supported in said frame and having apertures, lugs on the bottom of the pallet, said lugs having cavities in one of their faces, and said cavities being in alinement 115 with the apertures of the pallet and opening 120 through one side of the lugs, oppositely swinging plates between which the lugs are adapted to seat, one of said plates being adjustable to seat over the faces of the lugs having the cavities, and the other plate having lugs and being adjustable to position its lugs at the sides of the lugs of the pallet through which the cavities open to close up the same, pivotally connected angle levers 125 having one of their arms connected to the 130

plates, a shaft, a rocker arm on said shaft, links connecting the other arms of the angle levers with the rocker arm, and means for operating the shaft.

5 6. In a tile molding machine, a frame, a pallet removably supported in said frame and having apertures, lugs on the bottom of the pallet, said lugs having cavities in one

of their faces, and said cavities being in alignment with the apertures of the pallet 10 and opening through one side of the lugs, means for closing the open front and side of the cavities, and a gate at one end of the aforesaid frame for removal of the pallet.

In testimony whereof I affix my signature. 15

BYRON L. BACOT.
